UNITED STATES PATENT OFFICE

JOHN METZ, OF HOLLIS, NEW YORK, ASSIGNOR TO THE NESTLE-LE MUR COMPANY, OF NEW YORK, N. Y., A CORPORATION OF OHIO

HEAD PROTECTOR FOR HAIR WAVING

Application filed December 26, 1931. Serial No. 583,247.

In the art of permanent waving of growing hair on the head it is the universal practice to employ means for protecting the head in order to prevent excessive heat, as well as heated vapors and hot liquid, which reaches the temperature of boiling-water, from reaching the scalp of the subject whose hair is being subjected to the waving process, in which it is customary to use electric-heaters for the coiled hair-strands, around which latter it is usual to wrap absorbent-material which is saturated with a lotion. My present invention relates to this class of head protectors and my improvements provide a simplified form of device, when its peculiar and novel functions are considered, and one that can be quickly handled and applied by the hair-waving operator.

One of the important advantages of my improved device is that while it is spring-actuated with a normal tendency to close into gripping relation with an interposed object, the spring-actuated means is housed within the device itself and does not present any extraneous parts or projections which might interfere with the operator's quick manipulation of the device, or would be liable to catch in the hair when being applied and removed from the hair. Another advantage possessed by the device, is that while its spring action normally tends to close the device in operative position, yet before applying it, it may be set and held in wide open position, ready to be easily snapped into gripping operative position when required, by manually squeezing the device. There are other advantages possessed by my device and which will appear from the detailed description and illustrations herein set forth.

I have illustrated a type of my improved device, in the accompanying drawing, wherein;

Figure 1, shows a perspective view of the protector clip embodying my invention and as applied to a wound hair-strand.

Figure 2, shows an enlarged view of the parts shown in Fig. 1, the protector clip being in vertical cross-section on the plane indicated by line 2—2, in Fig. 1.

Figure 3, shows a top-plan view of the protector clip in closed position of disuse.

Figure 4, shows an underside view of the protector clip in the position shown in Fig. 2, and in partial horizontal section, as indicated by line 4—4, in Fig. 2, and looking in the direction of the arrows in said Fig. 2.

Figure 5, shows an underside view of the protector clip, as shown in Fig. 4, but in wide-open position and with a portion of one clip-member being broken away.

Figure 6, shows a perspective view of the coiled-spring detached.

Referring to the drawing, in which like numerals of reference designate like parts throughout, 1 and 2, indicate a pair of duplicate clip members or plates which are hinged together at one end by means of the rivet 3, so that the members are relatively movable edgewise in order to close and open with respect to each other, in gripping and releasing an interposed object. These members are made of suitable heat-insulating material, such as bakelite, fibre or other well known materials adaptable for this purpose, and their peripheries are formed on similar extended arcs, so that when closed in gripping positions, they together form a substantial circular outline. The inner edges of these members are indented or notched at their centers as indicated at 12 and 13, respectively, so that when the members are in gripping position on the hair-strand, they provide a circular opening 16, as indicated in Fig. 4; while in general outline the members are kidney-shaped.

A circular recess or cavity 4, is formed on the inner face of the section or plate 1, at one end thereof, and the recess is concentric with the pivot 3, which the recess surrounds. A circular raised part or boss 5, is formed

50

55

60

65

70

75

80

85

90

at the center of the recess around the pivotal axis. A coiled spring 6, is seated in the recess 4, with the central opening of the spring fitting around the boss 5. The respective 5 ends of the spring are bent outwardly with respect to the plane of the coil and at right angles thereto, but in opposite directions, as indicated at 7 and 8, in Fig. 6. The prong or bent end 7, is anchored in a hole 10, in the 10 bottom of the recess, as shown in Fig. 4, while the other prong 8, is fixed in a hole 11, in the face of the plate 2, as indicated in Fig. 2, and the construction and arrangement in such 15 that the coiled-spring acts to normally forcibly close the members into gripping positions and the force of the spring action is increased when the members are drawn apart into wide open positions, as shown in Fig. 5, as such movement serves to pull the ends of the 20 coiled-spring towards each other and thereby wind up the spring and increase its tension.

In order to limit the closing range of movement of the members 1 and 2, on each other and at a point beyond its gripping function, a 25 stop 17, is arranged on the upper face of the member 2, so that it is engaged by the inner edge of the member 1, as indicated in Fig. 3.

In order to hold the clip members in wide open positions against the action of the 30 spring, I provide friction means between the opposing faces of the two members, which comes into play when the members are opened widely. The means consists in a rounded projection or hump 18, on the inner face of member 2, which moves or snaps into a rounded 35 depression 19, formed on the inner face of member 1, and when these parts come together, the member are held open, as indicated in Fig. 5, thereby enabling the hair-waving operator to readily manipulate the 40 device and to quickly place it in operative position, by merely squeezing the members together, whereupon it will be snapped by the spring into gripping position around the hair-strand 14, which is shown as wound on a curling rod 15.

The pivot 3, being tubular in form, its ends are bent or swaged to provide external flanges which serve to rivet the members together, at the same time permitting them to 50 be swung or turned on the pivot, with the necessary freedom of movement.

It will be noted that the spring-actuating means is completely housed within the protecting clip and that there are no external projections thereof; that the structure presents a smooth exterior except for the rounded and flat flanges of the hinge member 3, and the rounded stop and friction locking means.

60 I wish to be understood as not limiting my invention to the specific constructions herein shown, as it is manifest that various modifications may be made in the several parts thereof, without, however, departing 65 from the spirit of the invention.

Having thus described my invention, what I claim and desire to secure by Letters Patent, is:—

1. A head protecting clip comprising superimposed members connected together and relatively movable edgewise so as to close and open with respect to each other to grip and release an interposed object, and interior spring-actuated means tending normally to close said members into gripping positions and located between the opposing faces of said members and housed thereby. 70 75

2. A head protecting clip comprising superimposed members connected together and relatively movable edgewise so as to close and open with respect to each other to grip and release an interposed object, and a coiled spring interposed between said members with its respective ends attached to said 80 85 respective members so that the spring is tensioned when said members are in open positions and tends to forcibly close said members into gripping positions.

3. A head protecting clip comprising superimposed members pivoted together and relatively movable edgewise so as to close and open with respect to each other to grip and release an interposed object, and a spring arranged between the opposing faces of said members and located around said pivotal axis, the respective ends of said spring being connected to the said respective members and acting to normally close said members edgewise with respect to each other and to be under tension when said members are opened. 90 95 100

4. A head protecting clip consisting in superimposed sections connected together and relatively movable edgewise so as to close and open with respect to each other to grip and release an interposed object, the inner face of one of said sections being provided with a recess, a spring located within said recess and having one end connected with one of said sections and the other with the other section so that the spring is put under tension when said sections are opened and acts to normally close said sections into gripping positions. 105 110

5. A head protecting clip consisting in superimposed members pivoted together and relatively movable edgewise so as to close and open with respect to each other to grip and release an interposed object, one of said members having a raised part extending around the pivotal axis, and a spring placed around said raised part, the respective ends of said spring being connected to said respective members and acting to normally close said members into gripping relation with each other and to be under tension when said members are opened. 115 120 125

6. A head protecting clip comprising superimposed members pivoted together and relatively movable edgewise so as to open and close with respect to each other to grip 130

and release an interposed object, one of said members being provided with a recess and the other member being provided with a raised part of less width than said recess and
 5 taking into the same, and a spring located within said recess and around said raised part, the respective ends of said spring being connected to the respective members and acting to normally close said members into gripping relation with each other and to be under tension when said members are opened.

7. A head protecting clip comprising superimposed members pivoted together and relatively movable edgewise so as to close
 15 and open relatively to each other to grip and release an interposed object, one of said members being provided on its face with a recess surrounding the pivotal axis and the other member being provided on its inner face
 20 with a raised part surrounding said pivotal axis and projecting into said recess, and a spring arranged within said recess and around said raised part and having its respective ends connected to said respective
 25 members so that the spring is tensioned when the members are opened and tends to forcibly close them into gripping positions.

8. A head protecting clip comprising superimposed members connected together and relatively movable edgewise so as to close
 30 and open with respect to each other to grip and release an interposed object, the inner face of one of said members being provided with a recess, and a coiled-spring located
 35 within said recess and having one end connected with one of said members and the other with the other said member and tending normally to forcibly close said members into gripping positions.

40 9. A head protecting clip comprising superimposed members connected together and relatively movable edgewise so as to close and open with respect to each other to grip and release an interposed object, spring-actuated means tending normally to close said members into gripping relation, and a stop located on one of said members and engaged by the other to limit the range of closing movement of said members.

45 10. A head protecting clip comprising superimposed members connected together and relatively movable edgewise so as to close and open with respect to each other to grip and release an interposed object, spring-actuated means tending normally to close said members into gripping relation, and friction means arranged between said members for holding said members in wide open positions against the action of said spring
 55 actuated means.

60 11. A head protecting clip comprising superimposed plates pivotally connected together at their ends by means of a member having its respective ends overturned or
 65 flanged to retain the plates together and said

flanges firmly engaging the exterior surfaces of the respective plates, to keep them in contact, a coiled-spring interposed between the opposing faces of said plates and having its ends attached respectively to said plates and being disposed concentrically with respect to said pivot member and acting to normally close the plates into gripping relation with respect to each other.
